Attorney,

UNITED STATES PATENT OFFICE

153,897

DESIGN FOR A FONT OF PRINTING TYPE

Dana Peterson, Newton, Mass.

Application June 9, 1947, Serial No. 139,555

Term of patent 3½ years

(Cl. D64—12)

To all whom it may concern:

Be it known that I, Dana Peterson, a citizen of the United States of America, residing at Newton, in the county of Middlesex and State of Massachusetts, have invented a new, original, and ornamental Design for a Font of Printing Type, of which the following is a specification, reference being had to the accompanying drawing, forming part thereof.

The drawing illustrates face views of a font of printing type showing my new design.

I claim:

The ornamental design for a font of printing type, as shown.

DANA PETERSON.
